Primary Examiner — Paula Allen Greene(74) *Attorney, Agent, or Firm* — Chun-Ming Shih; HDLS IPR Services(57) **CLAIM**

The ornamental design for a portion of wireless receiver, as shown and described.

DESCRIPTION

FIG. 1 is a perspective view of a portion of wireless receiver showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a second perspective view showing the portion of wireless receiver; and,

FIG. 9 is a third perspective view showing the portion of wireless receiver.

In the drawing, the claimed design is defined by the shaded surfaces; the broken lines depict unclaimed environment that forms no part of the claimed design.
